Primary Examiner — Paul D Bohannon(74) *Attorney, Agent, or Firm* — Jacob M. Ward; Ward Law Office LLC(57) **CLAIM**

The ornamental design for an outdoor high back chair, as shown and described.

DESCRIPTION

FIG. 1 is a top perspective view of an outdoor high back chair;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in the drawings illustrate portions of the article that form no part of the claimed design.
